MOBILE

Angelo J. Rosati, 7 Malquinn Drive,
Hopedale, Mass. 01747

Filed Oct. 28, 1965, Ser. No. 87,947

Term of patent 14 years

(Cl. D54—1)

FIG. 1 is a front, bottom and left side perspective view of a fluid conduit retainer for use in an automatic transmission of an automobile, showing my new design;

FIG. 2 is a front elevation view;

FIG. 3 is a top plan view;

FIG. 4 is a left side elevational view.

The dot-dash line showing in FIG. 2 of a series of conduits being retained when the retainer is in operating position is for illustrative purposes only.

FIG. 5 is a rear elevation view.

I claim:

The ornamental design for a fluid conduit retainer for use in an automatic transmission of an automobile, substantially as shown and described.
